Primary Examiner — Susan Bennett Hattan*Assistant Examiner* — Barbara Lohr(74) *Attorney, Agent, or Firm* — Shoemaker and Mattare(57) **CLAIM**

The ornamental design for a mosaic tile pattern, as shown and described.

DESCRIPTION

The sole FIGURE is a top plan view of a mosaic tile pattern, showing my design.

The sides and back of the mosaic tile pattern are unornamental and form no part of the design.

1 Claim, 1 Drawing Sheet
